UNITED STATES PATENT OFFICE.

RAYMOND P. MORSE, OF NEW YORK, N. Y.

DESIGN FOR AN OVERGAITER.

46,602.

Specification for Design.

Patented Oct. 27, 1914.

Application filed April 28, 1914. Serial No. 835,042. Term of patent 7 years.

To all whom it may concern:

Be it known that I, RAYMOND P. MORSE, a citizen of the United States, residing at the city of New York, borough of Brooklyn, county of Kings, and State of New York, have invented a new, original, and ornamental Design for Overgaiters, of which the following is a specification, reference being had to the accompanying drawing, forming a part thereof.

Figure 1 is an elevation of the overgaiter illustrating my new design, and Fig. 2 is an inverted plan view.

I claim—

The ornamental design for an overgaiter, as shown.

RAYMOND P. MORSE.

Witnesses:

KATE C. MORSE,
M. C. RODRIGUEZ.
